UNITED STATES PATENT OFFICE.

WILLIAM G. FARGO, OF JACKSON, MICHIGAN.

PENSTOCK.

No. 841,495.

Specification of Letters Patent.

Patented Jan. 15, 1907.

Application filed February 20, 1906. Serial No. 302,143.

To all whom it may concern:

Be it known that I, WILLIAM G. FARGO, a citizen of the United States, residing at Jackson, in the county of Jackson and State of Michigan, have invented certain new and useful Improvements in Penstocks, of which the following is a specification.

This invention relates to penstocks.

One object of the invention is to provide a reinforced-concrete penstock.

Another object resides in the construction of a reinforced-concrete structure of the stated or other variety wherein the reinforcing elements are disposed peculiarly with respect to the structure.

A still further object is to provide a concrete structure embodying such strength as to withstand the stress of hydrostatic pressure therewithin without the employment of metallic bulkheads or the interposition of iron channel or I-beam or similar structural shapes.

It is still further designed to build a structure of reinforced concrete provided with a concrete lining so arranged as to not receive stress due to the hydrostatic pressure within the structure.

With the above objects, together with others, the present invention consists in the combination and arrangement of parts hereinafter more fully described, shown in the accompanying drawings, and particularly pointed out in the appended claims, it being understood that changes may be made within the scope of the claims without departing from the spirit or sacrificing any of the advantages of the invention.

In the drawings, Figure 1 is a longitudinal sectional view of a single penstock, illustrating in connection therewith an intermediate base-wall for disposition beneath one wall of the penstock when said wall is forming a partition between two or more penstocks. Fig. 2 is a front elevation of the same. Fig. 3 is a top plan view. Fig. 4 illustrates a modified method of reinforcing the body-wall of the penstock. Fig. 5 is a plan view of a series of penstocks coupled up with one another and with the power-house, and Fig. 6 is a sectional view taken longitudinally through the series of penstocks.

Referring now to the accompanying drawings, and more particularly to Figs. 1 to 3, inclusive, there is shown a penstock-stall *a*, comprising a bottom 1, side walls 2, and a

closed end 3, with its opposite end open and exposed to the mill-race or other stream, these sides and the closed end being built sufficiently high to accommodate the usual head-water line *d*, the whole structure being composed, preferably, of reinforced concrete, as hereinafter described. The end 3 may be curved, as shown, or it might be catenary, parabolic, or the like in section.

The stall *a* is supported upon the main dam-wall 4, preferably of concrete, and the columns 5, of any suitable material, at the mouth of the tail-pit 6, there being an opening 7 formed through the bottom 1 intermediate said dam-wall and said column, in which is disposed a downwardly-flaring discharge draft-tube 8, supported upon said base at its minor end by the radial flange 9. A runner or turbine-wheel 10 is arranged within the stall with relation to said draft-tube. This turbine may be arranged horizontally upon the vertical shaft 11, or it may be disposed vertically upon a horizontal shaft, as will be explained hereinafter.

As is well known in this particular art, the stalls of penstocks are subjected to considerable strain or stress, due to internal pressure, the latter being so great in a full stock as to frequently cause leakage and seepage through the walls thereof. Especially is this internal pressure noticeable in a series of adjoining penstocks when an adjacent penstock is empty. Attempts have been made to overcome this serious defect by constructing the end, side walls, and bottom of the structure correspondingly heavy or thick to withstand the internal pressure. However, it has been found quite difficult to predetermine the necessary body and mortar constituents for the structure, so as to render the same water-tight and withstand the stress, particularly upon the side and the end walls. Aside from this disadvantage, it may be necessary to limit the thickness of the walls. It has also been attempted to build a strong and substantial penstock through the instrumentality of vertical channel-iron beams having elongated concrete blocks interposed therebetween, the iron beams being connected at their tops, above the upper ends of the concrete blocks, by tie-rods. It is claimed that this latter structure is such that the hydrostatic structure or loads on each of the walls being equal and acting in opposite directions the stress is upon the tie-rods, effecting an

equilibrium as to preserve the walls. In this structure just alluded to the side walls have been connected by a semicylindrical bulkhead composed wholly of metal and connected either to the said iron beam or to the elongated concrete blocks. Climatic conditions affect these tie-rods, which, together with the heavy stress thereupon and the separable bulkhead with respect to the side walls, has resulted in more or less distortion of the said elements with respect to one another and otherwise damaging the structure, resulting in the latter not being always water-tight.

As the result of considerable thought and practical experience and demonstration I have found it expedient to construct the stalls *a* of reinforced concrete, the end wall, which may or may not be semicylindrical, having the hoop or bight portion 11^a of the steel or other metallic reinforcing elements 11 embedded therein, preferably near the outer face thereof, with the legs of said reinforcing elements directed backward or upstream and downwardly on an incline from the closed end and into the foundation of the structure to firmly anchor the stall *a* with respect to its foundation. Thus the reinforcing elements 11 have a twofold function, in that they serve to strengthen and hoop the curved or other end of the structure and anchor the stall to the base or foundation of masonry or other suitable material. It will thus be seen that the end and side walls are formed, preferably, together and at the same time, thereby dispensing with separate ends or bulkheads. The side walls may, if desired, be reinforced in another manner—that is, by steel or other U-shaped reinforcing elements 12 embedded therein near the outer face thereof and directed upstream horizontally instead of upon an incline. If this second form or method of reinforcing be adopted, the inclined reinforcing elements 12' may be added and secured in any suitable manner to the legs of the elements 12 at their point of intersection, the inclined elements 12' being directed upstream and extending into the foundation to coöperate with the said U-shaped elements in the dual function of strengthening or hooping the closed end wall and anchoring the stall with respect to its foundation. This modification is shown in Fig. 4. As indicated at 13, a portion of the bottom 1 is provided with upper and lower reinforcing elements, tending to strengthen the front part of the structure to offset the weight or preponderance of tension at this point. Some advantages in disposing the reinforcing elements of the penstock-walls near the outer face thereof are that the tension in the end wall in particular is the greatest at its outer face, and the remainder of the concrete constituting the thickness of this wall is better retained and held in position with the reinforcing-rods or other elements

at the outer face, where they act in a sense, at least, in the manner of the netting on a balloon. At this point it might be stated that under certain conditions the penstock may be constructed upon the netting principle—that is to say, with the rods, fabric, or the like outside of the concrete. These methods of anchorage are substantial and give the penstock much stability against the downstream pressure.

To still further remedy the aforesaid evils of structures of the character described, I associate with the end of the penstock-stall a non-reinforced concrete lining 14, made to conform to the shape of said end and be held movably in contact with the inner face thereof and the inner faces of the side walls, too, if desired, by the internal or hydrostatic pressure within the stall. This lining may have an integral or separable non-reinforced foot 15, adapted to rest in movable contact with the bottom 1 of the penstock to protect the corner of the structure between the closed end and the bottom thereof. Since the lining is not fixedly secured to the end or bottom wall, it retains its normal condition against the action of the hydrostatic pressure or other conditions as regards its porosity when the structure is under stress. The result is that the penstock is provided with a lining possessing such qualification as to preclude the possibility of leakage or seepage at the end thereof, regardless of any slight or undue disintegration of the structure, due principally to internal pressure. It will be understood that the internal pressure does not place the lining under great, if any, tension, by reason of the fact that the lining is free of the structure and capable of movement in different directions. If preferred, the lining may be reinforced, and I wish it understood that I contemplate this feature, it being shown in the drawings. However, the lining will not be reinforced to a great extent, just sufficiently to aid in rendering it more or less flexible without causing it to lack the aforesaid qualifications, particularly as regards its porosity if placed under a slight stress or tension. The method of reinforcing the lining is not material. It is designed principally to prevent cracks forming in the concrete, due to slight tension when the lining moves on the outer wall of the penstock. This tension would be caused only by the friction of the lining on its base and outer side.

In Figs. 5 and 6 there is shown a double-end penstock plant, including four penstock-stalls 15, 16, 17, and 18. A shaft 19 is journaled longitudinally through the series of adjacent stalls and connected up with a generator 21', confined within a suitable housing 21. Disposed upon the shaft 19 is a series of four pairs of runners or turbine-wheels 22, there being a pair of runners or turbines in each stall arranged with respect to a common

draft-tube 23 of each stall and which communicates with the corresponding tail-pit 24. These runners or wheels are shown disposed vertically upon a horizontal shaft, in direct contradistinction to the mounting of the turbine in Figs. 1 and 2, and it is therefore obvious that a single stall may be provided with a horizontal shaft with a pair of turbine-wheels or runners mounted thereupon. Obviously three, four, or more turbines or runners may be disposed in each stall. It might be remarked, too, that if desired the horizontal shaft could be arranged at a direct right angle to the shaft shown in Figs. 5 and 6, whereby it could be directed through the stalls parallel with their side walls. It is thought that since this disposition of the shaft will not be characteristic features of the claims in this case, and owing particularly to the obviousness of it, illustration is deemed unnecessary.

As in the use of a single penstock, the walls of the series of penstocks are reinforced, and, if desired, the lining hereinbefore referred to may be employed for the purposes already stated.

In conclusion it is to be understood that a decked penstock may be constructed in accordance with the present invention and also that the body-walls of the structure may be reinforced by either or both methods of reinforcing herein described, either or both methods being subject to slight changes, according to the scope of the appended claims. Further, the lining need not necessarily extend throughout the length of the side walls of the stall, but, if desired, may be arranged at the closed end only.

What is claimed is—

1. A penstock having its walls reinforced near its outer faces, and a lining possessing flexibility covering those surfaces of the penstock subject to seepage.

2. A penstock comprising a stall, including a closed and open end and side walls, the vertical walls of the stall being of concrete reinforced, the reinforcing elements lying in inclined planes and hooped through the closed wall of the penstock, the free ends of the reinforcing elements extending in a downward upstream direction.

3. A penstock comprising a stall composed of reinforced concrete, the reinforcing elements extending round one end of the stall.

4. A penstock comprising a stall composed of reinforced concrete, the reinforcing means including elements hooped through one end of the stall.

5. A penstock comprising a stall composed of reinforced concrete, the reinforcing elements strengthening the stall and anchoring it to its foundation.

6. A concrete penstock having its walls reinforced near their outer faces.

7. A concrete penstock having its walls

reinforced near their outer faces, and a concrete lining covering those surfaces of the walls subject to seepage.

8. A concrete penstock having one of its walls reinforced near its outer face, and a flexible lining for said wall.

9. A concrete penstock comprising a stall having one of its walls reinforced near its outer face, and a flexible lining for said wall, the lining being free of the wall and held in contact therewith by internal pressure.

10. A concrete penstock comprising a stall having its end and side walls reinforced, the reinforcing elements of the side walls being directed upstream.

11. A penstock comprising a stall of reinforced concrete, and a reinforced-concrete lining for the stall, the lining having a reinforced-concrete foot portion for contact with the bottom of the stall.

12. A penstock comprising a stall of reinforced concrete, and a concrete lining for the stall, the lining having a foot portion for contact with the bottom of the stall.

13. A penstock comprising a stall of reinforced concrete, and a reinforced-concrete lining for the stall, the lining having a reinforced-concrete foot for contact with the bottom of the stall, the lining and its foot being free to move in different directions with respect to the stall and held in operative relation therewith by internal pressure.

14. A penstock comprising a stall of reinforced concrete, and a concrete lining therefor, the lining having a concrete foot for contact with the bottom of the stall, the lining and its foot being free to move in different directions with respect to the stall and held in operative relation therewith by internal pressure.

15. A penstock comprising a stall of reinforced concrete, and a flexible lining therefor, the lining having a foot for contact with the bottom of the stall, the lining and its foot being held in operative relation with respect to the stall by internal pressure.

16. A penstock comprising a stall, and a concrete lining therefor, the lining being held in place by hydrostatic pressure.

17. A penstock comprising a stall, and a reinforced-concrete lining held in operative relation to the stall by hydrostatic pressure.

18. A penstock comprising a stall, and a flexible lining therefor, the lining being held in place by hydrostatic pressure.

19. A penstock comprising a reinforced-concrete stall, provided with a draft-opening, a shaft journaled in said stall, turbine-wheels arranged within the stall with respect to said opening, and a concrete lining for the stall.

20. A penstock comprising a reinforced-concrete stall provided with a draft-opening, a shaft journaled in the stall, turbines upon the shaft within the stall and arranged with

respect to said draft-opening, and a reinforced-concrete lining for the stall.

21. A penstock comprising a stall provided with a draft-opening, a shaft journaled in the stall, a turbine disposed upon the shaft and arranged with respect to the said opening, and a lining for the stall, the lining being free of the stall and held in operative relation thereto by internal pressure.

22. A penstock comprising a stall provided with a draft-opening, a shaft journaled in the stall, a turbine disposed upon the stall and arranged with respect to the said opening, and a reinforced-concrete lining for the stall, the lining being free of the stall and held in operative relation thereto by internal pressure.

23. A penstock comprising a stall provided with a draft-opening, a shaft, turbines disposed upon the shaft and arranged with respect to the said opening, and a reinforced-concrete lining for the stall, the lining being held in place by internal pressure.

24. A penstock comprising a stall, and a lining for the stall, the lining being free of the stall and held in operative relation therewith by pressure.

25. A penstock plant comprising stalls, each provided with a draft-opening, a shaft extending through the stalls, turbines in each stall mounted upon said shaft, the turbines of each stall being arranged with respect to the corresponding draft-opening, and a lining for each stall non-adherent with respect thereto.

26. A penstock comprising a stall composed of reinforced concrete, the reinforcing elements being hooped around one end of the stall and inclosed within the latter and its foundation to strengthen the stall and anchor it to its foundation.

27. A penstock comprising a stall composed of reinforced concrete, the reinforcing elements being inclosed within the stall and its foundation to anchor the former to the latter.

28. A penstock comprising a stall composed of reinforced concrete, the reinforcing elements being inclosed within the stall and its foundation to anchor the former to the latter and a lining for the stall non-adherent to the latter.

29. A penstock comprising a stall and a flexible lining therefor, the lining being movable under stress to transfer the stress to the stall.

30. A penstock comprising a stall and a lining therefor, the lining being movable under stress to transfer the stress to the stall.

31. A penstock comprising a reinforced-concrete stall, and a lining therefor, the reinforcing elements anchoring the stall to its

foundation and the lining being movable under stress to transfer the stress to the stall.

32. A penstock comprising a reinforced-concrete stall, the reinforcements being directed upstream with portions embedded in the foundation of the stall to strengthen and anchor the latter.

33. A penstock comprising a reinforced-concrete stall, the reinforcements being directed upstream with portions embedded in the foundation of the stall to strengthen and anchor the latter, and a non-adherent lining for the stall.

34. A penstock comprising a stall, and a lining for the stall, the lining being non-adherent with respect to the stall and held in place by internal pressure.

35. A penstock comprising a stall, and a lining possessing flexibility covering those surfaces of the stall subject to seepage.

36. A penstock comprising a concrete stall having a closed end, the reinforcing elements, being hooped through the closed end of the stall and directed upstream.

37. A penstock comprising a stall of reinforced concrete, the reinforcing elements connecting the closed end, the sides of the stall and foundation of the latter to firmly anchor the stall.

38. A penstock comprising a stall of reinforced concrete, the reinforcing elements being hooped through the closed end of the stall and arranged to anchor the latter, and a flexible lining for the stall non-adherent thereto.

39. A penstock comprising a stall of reinforced concrete, the reinforcing elements being hooped through the closed end of the stall and having portions directed horizontally and upon an incline in an upstream direction to strengthen the walls of the stall and anchor the latter upon its foundation.

40. A penstock comprising a stall and means covering those surfaces of the stall subject to seepage said means being free of the stall.

41. A penstock comprising a stall, and flexible means covering those surfaces of the stall subject to seepage, said means being arranged to transfer the stress to the stall only.

42. A penstock comprising a stall and means arranged with respect to the stall to prevent seepage and to transfer the stress to the stall.

In testimony whereof I hereunto set my hand this 6th day of February, 1906.

WILLIAM G. FARGO.

In presence of—

NANNIE KING,
G. M. PATTERSON.
